[57] CLAIM

The ornamental design for a motor module cover, substantially as shown and described.

DESCRIPTION

FIG. 1 is a perspective view of a motor module cover illustrating my new design, wherein the environment in which the cover may be used is illustrated by the broken lines;

FIG. 2 is a front elevational view of the motor module cover of FIG. 1;

FIG. 3 is a side elevational view thereof;

FIG. 4 is a top plan view thereof; and

FIG. 5 is a bottom plan view thereof.

FIG. 1

FIG. 3

FIG. 2

FIG. 4

FIG. 5
